UNITED STATES PATENT OFFICE.

ROBERT JAMES ANDERSON, OF EL PASO, TEXAS, ASSIGNOR TO INTERNATIONAL FUEL CONSERVATION CO., OF PHOENIX, ARIZONA, A CORPORATION OF ARIZONA.

COMBUSTION PROCESS.

Application filed March 6, 1919. Serial No. 281,037.

To all whom it may concern:

Be it known that I, ROBERT J. ANDERSON, a citizen of the United States, residing at El Paso, in the county of El Paso and State 5 of Texas, have invented certain new and useful Improvements in Combustion Processes, of which the following is a specification.

My object is to provide a new combustion process wherein the fuel and air are 10 admitted to the combustion chamber under such nice regulation and wherein they combine in such manner that substantially all of the carbon of the fuel and the oxygen unite in such manner as to minimize possibility 15 of excess oxygen and whereby there is insured liberation of substantially all of the heat units which may be derived from the union of the fuel and air.

In carrying out my process, there is jettied, 20 sprayed, or otherwise forced or introduced into a closed combustion chamber, at an angle, preferably nearly a right angle, to the direction of final travel of the gases derived from combustion as they flow toward 25 their point of utilization, numerous streams of air and fuel which play across or intersect at a very great number of points. The fuel may comprise finely divided coal, coke, or other solid carbonaceous material, or may 30 be any hydrocarbon or gaseous fuels. Whatever fuel is used, it will be introduced into the combustion chamber in connection with air or steam jets under pressure in a manner that not only the exterior of the 35 body or mass of flame derived from combustion will be converted into CO_2 , but the entire interior of the mass or body of flame will be similarly converted instead of escaping, as has heretofore been the case, in 40 the form of incompletely combusted carbon and, instead of a large percentage of the fuel passing off as waste without liberation of heat units, substantially the entire body of fuel introduced within the combustion 45 chamber will combine with the oxygen of the air jets, all of which results in liberation of a maximum number of heat units with a minimum of uncombined carbon and oxygen.

The introduction of the jets or sprays of 50 air and fuel into the combustion chamber is not restricted to any particular means. However, to insure as nearly perfect combustion as may be possible, I prefer to jet or spray the fuel in under suitable pressure 55 and to disseminate the air throughout the

cross-playing streams of fuel by forcing it in through perforated tubes of refractory material, or like distributing devices, located within the combustion chamber, the jets or streams of fuel playing cross-wise 60 relative to the tubes and, in turn, being shot through and through by the oxygen derived from the numerous fine jets of air issuing from said tubes.

The cross-jetting of the fuel and air at 65 an angle, preferably nearly a right angle, to the direction of final travel of the gases derived from combustion as they flow toward their point of utilization, accomplishes an important function in effecting substantially 70 complete combustion. Instead of projecting the fuel at high velocity toward the point whence the products of combustion are to pass to the point of utilization thereof as has heretofore been the common practice and 75 by which the proper development or liberation of the heat units from the fuel is prevented, my new process results in the retaining of the gases in the combustion chamber until the complete admixture of the 80 oxygen and the carbon is accomplished and the heat units fully liberated.

In the accompanying drawings:

Figure 1 is a vertical section of a steam boiler furnace equipped with combustion 85 apparatus for practicing my process.

Fig. 2 is a vertical section on line 2-2 of Fig. 1.

Fig. 3 is a detail section showing one of the nozzles for injecting the fuel, and the 90 manner in which it is sealed in the wall of the combustion chamber; and

Fig. 4 is a detail section illustrating the manner of securing one of the refractory air 95 distributing tubes.

My process may be put to various uses but I have illustrated it in the drawings as practiced in connection with a steam boiler furnace.

The boiler appears at 66 as having combustion chamber 67. The products of combustion pass from the combustion chamber 67, under the arch 68, through flue 69 to the boiler, thence returning through the boiler flues to the chimney or smoke stack 100 70. Obviously the process resides in the novel manner of production of combustion and not in the particular boiler illustrated.

Extending partially across the combustion chamber are a number of nozzles or air dis- 110

tributing tubes 15 of some suitable refractory material. These tubes or distributors extend through the wall of the combustion chamber and are sealed therein by fire clay 16, Fig. 4. The tubes or pipes 15 are provided with numerous openings or perforations 17 which are relatively small so that the air will issue therefrom substantially at right angles to the lengths of the tubes 15 10 in the form of numerous fine jets or sprays. As many of the air distributors 15 as may be desired, or as may be found necessary, can be used. I have shown three rows thereof, at different levels, but in other forms of 15 apparatus for practicing the process a greater or lesser number of these air distributors may be used. The air distributors receive air in suitable volume and under suitable pressure, from pipes 71, each pipe having a valve 72 to control the admission 20 of the air; the pipes 71 may receive their air from any suitable source. The pipes 71 are sealed where they enter the distributors 15 by fire clay wads 21, Fig. 4. The air distributors 15 of the respective rows, are arranged in stepped or staggered formation for a purpose which will presently appear.

The fuel is jetted or sprayed into the combustion chamber 67 in finely divided form. 30 Such fuel may comprise finely divided coal, coke, or other solid carbonaceous material, or may be any hydrocarbon or gaseous fuel. I have illustrated how a hydrocarbon oil may be jetted or sprayed into the combustion chamber 67 by the use of ordinary air or steam pressure nozzles, but it is to be understood that any suitable, or preferred, means for jetting or spraying any fuel which may be used, can be employed for 40 this purpose. In Fig. 3 there is shown an ordinary jetting or spraying nozzle or distributor 73 which may be suitably sealed in the wall of the combustion chamber by fire clay 23. The fuel, for instance hydrocarbon oil, is introduced to the nozzles through pipes 74 having valves 76 connected to any suitable source of supply. The air or steam for spraying the oil is introduced to the nozzles by pipes 75 having valves 77. 45 50 The fuel distributing nozzles 73 are so located that they will cause the fuel to be jetted or sprayed in finely divided form crosswise or at an angle to the lengths of the

air distributors 15, and crosswise in relation to many of the air jets issuing from the 55 perforations 17. The cross play of the finely divided fuel jets and the direction of play of the air jets issuing from the perforations 17 is, also, at an angle, preferably nearly a right angle, to the direction of final travel 60 of the gases derived from combustion as they flow toward their point of utilization. The cross play or intersection of the jets or sprays of fuel and the jets of air from the distributor 15 effects substantially complete 65 combustion and substantially complete liberation of the heat units before the flow of gases to be subsequently utilized proceeds toward the outlet or outlets from the combustion chamber. Consequently, my process 70 obtains a new result, due to the cross play and interaction of the fuel and oxygen derived from the air jets to the end that not only the exterior of the body or mass of flame derived from combustion is converted 75 into CO_2 but, also, the entire interior of the mass or body of flame is thus converted. The staggered relationship of the rows of air distributors 15 to the nozzles 73 insures that the air issuing from the perforations 80 17 of each air distributor 15 will form a complete admixture with the jetted or sprayed fuel from the nozzles 73.

The valves 72, which control the supply of air to the distributors 15, and the valves 85 76 and 77, which control the spraying of the fuel, enable any desired regulation to be had so that the process may be practiced in connection with any furnace, kiln, boiler, or other installation, according to requirements. 90

What I claim is:

A process of combustion comprising the forcible injection into a combustion chamber of a plurality of streams of finely divided fuel, igniting the fuel of each stream, thereby producing a moving mass of burning fuel, introducing into the interior of said moving mass, through the side thereof, a body of air, and forcibly discharging said air into a plurality of jets at abrupt angles to the axis of said body from said body of burning fuel. 95 100

In testimony whereof I affix my signature.

ROBERT JAMES ANDERSON.
